UNITED STATES PATENT OFFICE.

BENJAMIN ZIMMER, OF MINNEAPOLIS, MINNESOTA.

TABLE.

1,358,353.

Specification of Letters Patent.

Patented Nov. 9, 1920.

Application filed October 25, 1916. Serial No. 127,604.

To all whom it may concern:

Be it known that I, BENJAMIN ZIMMER, a citizen of the United States, resident of Minneapolis, county of Hennepin, State of Minnesota, have invented certain new and useful Improvements in Tables, of which the following is a specification.

The object of my invention is to provide a table which can be easily and quickly increased or decreased in the size or area of its top to adapt it for a library or living room table or for a dining or breakfast room table.

Other objects of the invention will appear from the following detailed description.

The invention consists generally in various constructions and combinations, all as hereinafter described and particularly pointed out in the claims.

20 In the accompanying drawings forming part of this specification,

Figure 1 is a plan sectional view of my improved table in its collapsed or folded condition,

25 Fig. 2 is a transverse sectional view of the same,

Fig. 3 is a plan sectional view, showing the table expanded,

Fig. 4 is a sectional view showing the leaf 30 raised to the level of the table top and near the end of its upward movement,

Fig. 5 is a transverse sectional view of the table closed,

Fig. 6 is a transverse sectional view of 35 the table in its open position,

Fig. 7 is a view corresponding to Fig. 4, taken on a section line at right angles substantially to the section line of Fig. 6, with the leaf unfolded between the sides of the 40 table top.

In the drawing, 2 represents the legs of the table of any ordinary or preferred construction. 3 represents side bars and 4 end bars between the connecting or side bars. 45 5 represents rails, having groove and tongue connections with a stationary rail 5', disposed preferably between the rails 5 and mounted on the tops of the legs. The bars 5 are connected respectively to table top sections 6 and 7 and are movable back and forth on the rails 5' to open and close the table top. This manner of mounting the top sections on the sliding rails is of ordinary construction in tables and I make no 55 claim to the same herein.

Between these sliding bars at right angles

substantially thereto I provide rails 8 in parallel relation with one another upon opposite sides of the middle portion of the table. These rails are secured to the bars 60 9 which extend horizontally between the upper portions of the legs and between the sliding bars 5, and are suitably secured to rails 5'. The inner faces of the rails 8 are provided with cam grooves 10 having horizontal end portions 11 and 12 and between the rails I provide a leaf composed preferably of sections 13 and 14, having their abutting ends hinged together by means of invisible hinges 15, which I do not illustrate 70 in detail, as they are ordinary stock hinges.

A cross bar 16 is provided on the section 14 near one end, having gudgeons 17 to slide in the grooves 10. The lower ends of the grooves are near the lower edges of the 75 rails 8 and the upper ends of the grooves are near the upper edges of these rails and when the leaf sections are folded, they will drop down between the rails 8 and the sliding bars of the table top and allow the bars 80 to be moved toward one another to close or contract the table, the top sections having the usual dowel pins 18 and sockets 19 to register when the sections of the top are moved against one another.

The ends of the lower leaf section 14 have grooves 19' therein to receive the pins 18 when the leaf is raised to a level with the table top, and the upper leaf section 13 has notches 20 therein to receive the dowel pins 90 at the opposite end of the top sections and thereby the leaf will be securely locked in its raised position. As shown plainly in Fig. 7, the upper ends of the grooves 10 are substantially horizontal and the gudgeons 95 seated therein will be firmly supported and the upper surface of the leaf, when raised and unfolded, will be securely supported on a level with the table top, even under the weight of heavy articles which may be 100 placed on the table. I also prefer to provide a cam block 21 with which the end of the lower leaf section contacts when the table is opened and the leaf is raised. The substantially horizontal upper portions of 105 the grooves 10 insure a stable support for the folding leaves and eliminate any possibility of their sliding downward accidentally in the cam before the user desires to close the table.

In using the table, the top sections are pulled apart to expose the space between

them. The operator will then grasp the free end of the upper leaf section 13 and raise it away from the other section, at the same time exerting sufficient pressure on the lower section to cause it to slide upwardly in the grooves until it is on a level with the table top and the end of the lower leaf section in alinement with the corresponding ends of the top section. The upper leaf section is then dropped down upon the dowel pins and the table is ready for use. As the sections ride up in the cam grooves, the end of the leaf will strike the block 21 and be guided thereby upwardly to the space between the sliding sections of the top.

To fold the table, the upper leaf section may be raised or tilted over upon the lower section and the two moved endwise, with the gudgeons sliding in the grooves and the end of the lower section following a guide 21 until the sections are below the level of the table top, when the top sections may be moved toward one another to close the gap between them and conceal the leaf.

In various ways the details of construction herein shown and described may be modified and still be within the scope of my invention.

I claim as my invention:

1. The combination, with a table top composed of sections mounted to move away from or toward one another to expose or close the gap between them, a leaf composed of hinged sections mounted to slide in guides from a point below the level of said top sections to a position substantially in alinement therewith the lower leaf section supporting the upper section, the upper portion of the guides for said leaf section adjusting the lower leaf section with its end in alinement with the adjacent ends of the table top when the sections are raised, the upper leaf section being lifted from the lower leaf section and turned downwardly to position its end in alinement with the opposite edge of the table top.

2. The combination, with a table top composed of sections mounted to move away from or toward one another to expose or close a gap between them, a leaf composed of sections placed end to end and hinged together, side guides wherein said leaf is movable vertically from a position beneath said top to a position between the separated sections thereof, and an end guide having a curved surface whereon said sections are slidable.

3. The combination, with a table top composed of sections mounted to move away from or toward one another to expose or close a gap between them, of a leaf composed of sections hinged together and mounted to move from a position below the level of said table top sections to a point on

the level therewith, said leaf sections when in their raised position having a horizontal sliding movement, the under leaf section having means for interlocking with the abutting edges of the top sections and the upper leaf section having means for interlocking with the opposite ends of said top sections when said upper leaf section is lifted and swung down to a position between said top sections and on a level therewith.

4. The combination, with a table top composed of sections mounted to move away from or toward one another to expose or close a gap between them, said sections having pins in their opposing edges, of a leaf composed of sections hinged together and mounted to be unfolded and moved into the gap between said top sections, one of said leaf sections having longitudinal recesses therein to receive the pins at one end of said top sections and the other leaf section having notches therein to receive the pins at the other end of said top sections.

5. The combination, with a table top composed of sections mounted to move away from or toward one another to expose or close a gap between them, of a leaf composed of sections hinged together and mounted to move from a position below the level of said table top sections to a point on a level therewith, said leaf sections when in their raised position having a horizontal sliding movement, the under leaf section having comparatively long recesses in its edges to receive pins provided in the abutting edges of said top sections and the upper leaf section having notches in its upper surface to receive pins provided in the opposite ends of said top sections when said top section is lifted and swung down to a position between said top sections and on a level therewith.

6. The combination, with a table top composed of sections mounted to move away from or toward one another to expose or close the gap between them, of a leaf section composed of upper and lower members hinged together at one end and mounted in inclined guides beneath the table top and extending transversely thereof for movement of said leaf section from a position below the level of said top to a point where its lower member will be in alinement with said table top sections, the upper leaf member when lifted and folded down to a horizontal position on a level with the lower leaf member co-operating with said lower member to fill the gap between the table top sections and said leaf members having means for interlocking with said table top sections.

7. The combination, with a table top composed of sections mounted to move away from or toward one another to expose or

close the gap between them, a leaf composed of hinged sections mounted to slide in guides transversely of the table from a point below the level of said top sections to a position substantially in alinement therewith, the upper portion of the guides for said leaf section being substantially horizontal for adjustment of the lower leaf section with its end in alinement with the

adjacent ends of the table top, the other leaf section normally lying upon the lower leaf section and being lifted and turned downwardly to position its end in alinement with the opposite edge of the table top.

In witness whereof I have hereunto set my hand this 18th day of October 1916.

BENJAMIN ZIMMER.
